To all whom it may concern:

Be it known that I, Ernest L. Shepard, a citizen of the United States, residing at Fairfield, county of Somerset, State of Maine, have invented a new, original, and ornamental Design for a Fragile Article Support, of which the following is a specification, reference being had to the accompanying drawing, forming part thereof.

Fig. 1 is a plan view showing the upper face of a fragile article support embodying my new design.

Fig. 2 is a section on the line 2—2, of Fig. 1, and

Fig. 3 is a fragmentary perspective.

I claim:

The ornamental design for a fragile article support, as shown.

ERNEST L. SHEPARD.
